CRUSHING MACHINE

Pascal Schilz, Los Angeles, Calif.

Application April 20, 1938, Serial No. 203,052

2 Claims. (Cl. 83—53)

My invention relates to a crushing machine of the particular type having a reciprocating jaw that cooperates with a yielding jaw for crushing and reducing to the desired size, rock, ore and the like and among the principal objects of my invention are, to generally improve upon and simplify the construction of the existing forms of similar crushing machines, to provide a crushing machine wherein wear resulting from the grinding action of the material that is being ground on the crushing faces of the jaws is minimized; further, to provide a crushing machine that has a relatively large capacity with minimum power requirements and further, to provide a crushing machine wherein unnecessary crushing of the rock or ore after the reciprocating jaw has done its work, is eliminated, thus effecting a material reduction of strains on the movable jaw and its operating parts.

Further objects of my invention, are to provide a crushing machine wherein a large proportion of the weight of the reciprocating jaw is carried by a spring or springs, thus minimizing power requirements in the operation of said jaw and further, to provide an eccentric and toggle link arrangement for imparting movement to the reciprocating jaw, which arrangement is effective in causing the lower portion of said jaw which accomplishes the crushing operation to move, in a substantially semi-elliptic path, so that said jaw cooperates to the greatest possible degree with the yielding jaw in effecting rock and ore crushing operations. As a result of moving the lower portion of the reciprocating jaw in a substantially semi-elliptic path of travel, undue wear of the crushing faces of both jaws is eliminated and also, unnecessary grinding of the rock or ore after it has been crushed to the desired degree is eliminated, particularly during the period immediately following the time that the crushing face of the reciprocating jaw reaches its peak of crushing forces applied to the rock or ore between the lower portion of the crushing face of the reciprocating jaw and the opposite crushing face of the yielding jaw.

A further object of my invention, is to provide a crushing machine wherein direct or straight line travel of the reciprocating crushing jaw in performing its crushing operations is eliminated and to construct said jaw actuating means so that it moves the crushing face thereof forwardly and downwardly during the greater portion of its crushing action.

A further object of my invention is, to provide simple, convenient and readily accessible means

for adjusting the position of the yielding jaw of the crusher toward and away from the reciprocating jaw and to mount the lower portion of the yielding jaw on a simple, practical and readily adjustable spring cushion.

With the foregoing and other objects in view, my invention consists in certain novel features of construction and arrangement of parts that will be hereinafter more fully described and claimed and illustrated in the accompanying drawings in which:

Fig. 1 is a side elevational view of a crushing machine constructed in accordance with my invention.

Fig. 2 is a vertical section taken lengthwise through the center of the crushing machine as indicated by dotted line 2—2 in Fig. 4.

Fig. 3 is a diagrammatic view illustrating the substantially semi-elliptic path of travel of the lower end of the movable crushing jaw.

Fig. 4 is a horizontal section taken approximately on the line 4—4 of Fig. 1 and Fig. 2.

Fig. 5 is an enlarged rear elevational view of the machine with parts thereof in section.

Fig. 6 is a detail sectional view showing the means for adjusting the position of the upper end of the yielding jaw.

Fig. 7 is an enlarged detail section of the lower ends of the jaws of the crusher and showing the substantially semi-elliptic path of travel of the lower end of the reciprocating jaw.

Referring by numerals to the accompanying drawings which illustrate a preferred embodiment of my invention, 10, 10 designate the side walls of the machine which are preferably of cast construction, and connecting these side walls at various points are transversely disposed frame members 11, preferably cast, and the ends of which are secured to the side walls in any suitable manner. Mounted on top of the side walls is a hopper 12 that receives the rock or ore to be crushed and which delivers same into the space between the upper portions of the jaws.

The reciprocating jaw 13 carries on its face a plate 14 of hard, wear-resisting metal, the outer face of which is flat and said plate being detachably retained on the face of the jaw in any suitable manner, preferably by means of a clamping plate 15 that is applied to the upper end of jaw 13 and which overlies plate 14. This construction enables the face plate which receives the wear incident to crushing operations, to be easily and quickly removed and replaced when broken or when worn to such a degree as to render it unfit for service.

Seated in the side walls 10 to the rear of the upper portion of jaw 13 is a transversely disposed rod 16 on which is mounted a sleeve 17 and bearing on said sleeve for rocking movement is one end of a rocker frame 18, the forward end of which has a rocking bearing on the upper rear portion of jaw 13.

This rocker frame 18 performs the functions of a strut to maintain the upper portion of jaw 13 in proper operative position. Mounted between the upper portions of the side walls 10 to the rear of jaw 13 and above rod 16, is a housing 19 in which is arranged for sliding movement a tube 20, the upper end of which carries a nut 21 that bears on the upper end of an expansive spring 22 and which latter functions as a lifting spring to yieldingly hold the jaw 13 at its upper limit of movement. Screw-seated in the lower portion of tube 20 is the upper end of a rod 23, the lower end of the latter being pivotally connected to the upper rear portion of jaw 13 just below the bearing for the forward end of the frame 18.

As jaw 13 moves toward or away from the opposite jaw of the crushing machine, tube 20 and rod 23 move longitudinally together through housing 19 and, the point of pivotal connection between the lower end of rod 23 and jaw 13 provides a yielding support for said jaw.

Journalized for rotation in suitable bearings on the side walls 10 to the rear of the lower portion of jaw 13 is a shaft 24, one or both ends of which carry belt wheels 25 and mounted on said shaft between the side walls is an eccentric 26.

Passing through the ends of the levers 28 opposite the ends that are mounted on the eccentric 26, is a shaft 31 and journaled on this shaft 31 are the upper ends of links 32, the lower ends thereof being journaled on pins or a shaft 33, the ends of which are seated in the side walls 10.

Short links 32a have their ends mounted respectively on shaft 29 and shaft 31, thus combining with the levers 28 in producing a toggle connection between shaft 24 and the lower end of jaw 13.

In Fig. 4 of the drawings I have illustrated three separate levers 28, the outer ends of all of which levers are provided with anti-friction bearings 27 that engage the eccentric 26 on shaft 24 and the shaft 31 that passes through the inner ends of these three levers is connected by a pair of links 32a to the pin 29 that is seated in the lower portion of the jaw 13 and a pair of links 32 connect shaft 31 with pin or shaft 33.

Under normal conditions or with the crushing surface of plate 14 occupying a substantially vertical plane as illustrated in Fig. 2, the axes of shaft 24 and pin 29 occupy the same horizontal plane and the links 32 occupy a plane that is slightly inclined with respect to the vertical, with the axis of shaft 31 slightly closer to the vertical plane occupied by the face of plate 14, than the axis of pin or shaft 33.

The arrangement just described is effective in causing the lower edge of the face of plate 14 to traverse a substantially semi-elliptical path so that on its movement toward the lower portion of the yielding jaw it moves upward and forward, thence forwardly and downwardly during the final portion of its movement toward said yielding jaw and then in a substantially straight horizontal line on its rearward movement or movement away from the yielding jaw. This path of travel of the lower portion of the movable jaw is diagrammatically illustrated in

Fig. 3, also in Fig. 7. This arrangement is also effective in eliminating direct straight line motion of crushing jaw 13 during its crushing stroke and minimizes undue grinding wear on the crushing faces of both jaws.

The advantage gained by causing the lower portion of the jaw 13 to travel in a substantially semi-elliptic path as illustrated in Fig. 3 is, that during the final half of its crushing movement against jaw 34, the lower portion of said jaw 13 is caused to move forwardly and downwardly so as to engage and crush with a semi-rolling movement the material that is engaged between the lower portions of the two jaws.

It has been demonstrated in long practice that by causing the reciprocating jaw or the lower portion thereof, to move with a combined forward and downward movement against the material that is passing between the two jaws, said material is crushed to much better advantage and with the applying of less power to the crushing jaw than where the same is moved in a practically straight line against the material passing between the two jaws. Such action is especially effective in minimizing the grinding action and wear, particularly on the lower portion of the face of the reciprocating jaw.

During this movement of the jaw 13, the lower portion thereof moves to a much greater degree than the upper portion, due to the fact that the upper portion of the jaw is connected to the frame by a sliding connection, including rod 23 and tube 20, which permits the upper portion of the jaw to move upwardly and downwardly in an inclined path, while the lower portion of the jaw swings backward and forward, as well as in a substantially vertical direction, due to the toggle arrangement between the lower portion of said jaw 13 and the eccentric 26, so that the lower portion of said jaw moves in a substantially semi-elliptic path as illustrated in Figs. 3 and 7 and, which movement eliminates excessive wear on the lower portion of the face of the jaw.

Positioned between the side walls 10 directly in front of the reciprocating jaw, is a yielding or adjustable jaw 34 that is supported for swinging movement upon a shaft 35, the ends of which pass through horizontally disposed slots 36a that are formed in the upper front portions of the side walls 10. Removably positioned on the face of jaw 34 is a crushing plate 36 of hard, wear-resisting metal and the lower portion 37 of the face of this plate occupies a position parallel with and spaced slightly apart from the lower portion of the vertical face of plate 14. The lower end of liner 36 is supported on jaw 34 by a slightly inclined shoulder that is formed on the lower portion of the face of said jaw 34, as illustrated in Fig. 7, and the upper end of said liner is held against the jaw by the heads of bolts 36b that pass through the upper portion of jaw 34. A portion 38 of the face of plate 36 immediately above the portion 37 occupies a plane that is slightly inclined with respect to the plane occupied by the plate 14 when the same is in substantially vertical position as illustrated in Fig. 2. That portion 39 of the face of plate 36 above the inclined portion 38 occupies an inclined plane that is several degrees greater than the plane occupied by the inclined portion 38.

By mounting the ends of shaft 35 in the slots 36, the upper portion of jaw 34 may be adjusted toward or away from the upper portion of jaw 13 and to accomplish such adjustment, blocks 37 are mounted on the ends of shaft 35 adjacent the

side walls 10 and seated in said blocks and retained therein by pins 39a are the inner ends of horizontally disposed threaded rods 39. Each rod is mounted to pass freely through pairs of bearings 40 that are secured on the outer faces of the side walls 10 and screw seated on each rod between the members of each pair of bearings is a worm wheel 41. Engaging the teeth of the worm wheels 41 are worms 42 that are secured to the transversely disposed shaft 43, the latter being journaled in the side walls 10 and carried by the outer ends of shafts 43 are discs 44 that are adapted to be engaged by a suitable tool to rotate said shaft, thus transmitting rotary motion to the worms 42 and worm wheels 41, thereby moving the threaded shafts 39 lengthwise through bearings 40.

The outer ends of the threaded rods 39 are supported by a transversely disposed beam 39a that extends transversely of the machine a short distance away from the end wall of the housing (see Fig. 1).

As a result of the construction just described, the upper end of jaw 34 which is not spring cushioned may be conveniently adjusted toward and away from the upper end of jaw 13.

In the form of crushing machine illustrated, jaw 34 is mounted in the machine so that it will yield outwardly away from the lower portion of jaw 13 against the resistance offered by a spring 35 and the shaft 35 provides the axis for the yielding movement of said jaw. In order to make jaw 34 non-yielding, it is only necessary to construct same without the spring cushion arranged rearwardly of its lower end and to rigidly connect said lower end to the frame of the crusher.

In the present construction, a transverse rail 45 is pivotally mounted on a transverse rod 46 that is seated in the lower rear portion of jaw 34 and seated in rail 45 are the inner ends of a series of horizontally disposed rods 47. The outer portions of these rods 47 pass through a rail 48 and the ends of the rods that extend beyond said rail are threaded for the reception of nuts and washers 49. Positioned on the rods 47 between the rails 45 and 48 are expansive coil springs 50 which combine to form a spring cushion that yieldingly resists the outward swinging movement of the lower portion of jaw 34.

The means for adjusting the position of jaw 34 include rods 51 that are mounted for sliding movement in the lower portions of the side walls 10 and the outer ends of said rods being mounted on trunnions 52 that project from the ends of rail 48. Those portions of the rods 51 that project into the side walls 10 are threaded, as designated by 53, for the reception of threaded sleeves 54 that operate between stops or partitions within the side walls 10 and carried by each sleeve 54 is a worm wheel 55. Journaled in the lower portions of the side walls 10 below the worm wheels 55, is a transverse shaft 56 and mounted thereupon are worms 57 that respectively engage the worm wheels 55. The ends of shaft 56 that project beyond the side walls 10 carry discs 58 that are adapted to be engaged by suitable tools so that the shaft may be rotated and through worms 57, worm wheels 55 and threaded sleeves 54, longitudinal movement is imparted to the rods 51 to move the jaw 34 toward or away from jaw 13. Tension of springs 50 is adjusted by means of nuts 49 that are seated on rods 47.

In the operation of my improved crushing ma-

chine, the rock or ore to be crushed passes from hopper 12 into the space between the upper portions of the jaws and passes downward as the reciprocating jaw 13 is operated.

Shaft 24 is driven and eccentric 26 mounted upon said shaft imparts eccentric movement to the outer end of levers 28. Due to the connection of the inner ends of the levers 28 with the lower end of jaw 13 and the fulcruming of said levers on the shaft 31 carried by the upper ends of links 32 which swing on the fixed axis 33, the lower edge of the front face of plate 14 carried by jaw 13 traverses a substantially semi-elliptical path. During the downward movement of jaw 13 and which occurs during the latter portion of its movement toward jaw 34, the weight of said jaw 13 is yieldingly resisted by the springs 22 and the power stored in said springs during such downward movement acts to lift said jaw during the first half of its succeeding movement toward jaw 34.

During the movement of jaw 13, its upper rear portion bears against the inner end of member 18, the outer end of which bears on shaft 16.

The lower portion of the crushing face of jaw 13 during its return movement traverses a substantially straight horizontal path as indicated in Fig. 3 and during such movement the ore or rock moves downward in the space between the two jaws and on the succeeding movement of jaw 13 toward jaw 34, the rock or ore is crushed to the desired degree of fineness and on the succeeding rearward movement of jaw 13 the crushed material discharges from between the lower portions of said jaws.

As hereinbefore described, the upper end of the yielding jaw may be adjusted toward or away from the upper portion of movable jaw 13 by proper manipulation of shaft 43 and the tension of the spring cushion that yieldingly resists the movement of the lower portion of jaw 34 away from the lower portion of jaw 13 may be accomplished by proper manipulation of the shaft 56.

An especially desirable feature of my invention is the eccentric and toggle connection between the power shaft 24 and the lower portion of the crushing jaw 13, for by such connection the movement imparted to the lower portion of the crushing jaw minimizes wear on the crushing faces of the jaws and also eliminate unnecessary grinding or crushing of material which would otherwise occur during a portion of the rearward movement of the crushing jaw, if the eccentric were connected directly to said crushing jaw.

Thus it will be seen that I have provided a crushing machine that is relatively simple in construction, inexpensive of manufacture and very effective in performing the functions for which it is intended.

Further advantages gained by my improved construction and particularly the provision of the eccentric and toggle arrangement for operating the crushing jaw, are a more advantageous distribution of strains developed during operation of the machine, the development of a maximum degree of crushing power, comparatively large output of crushed material for a given amount of horse power required to operate the machine and the minimizing of grinding wear upon the crushing faces of the jaws.

It will be understood that minor changes in the size, form and construction of the various parts of my improved crushing machine may be made and substituted for those herein shown.

and described, without departing from the spirit of my invention, the scope of which is set forth in the appended claims.

I claim as my invention:

1. In a crushing machine, a frame, a pair of jaws mounted for operation in said frame, spring suspension means between the upper portion of one of said jaws and said frame, a pivoted strut providing a rocking bearing for the upper portion of said spring suspended jaw and power driven operating means connected to the lower portion of said spring suspended jaw for causing the lower portion thereof to traverse a substantially semi-elliptic path in its movements to and from the other jaw, which power driven operating means includes an eccentric, a lever having one end mounted on said eccentric, a link pivotally connected to the other end of said lever and to the lower portion of said jaw, a second link arranged substantially parallel with the jaw, the lower end of which second link is pivotally connected to the frame, the upper end of said second mentioned link being pivotally connected to the connected ends of said lever and first mentioned link and the point of pivotal connection between 25

said lever and the two links being disposed in a plane above the horizontal plane occupied by the axis of the eccentric and the axis of the pivotal connection between the first mentioned link and the lower end of the jaw.

2. In a crushing machine, a frame, a pair of jaws positioned in said frame, spring suspension means between the upper portion of one of said jaws and said frame, a pivoted strut providing a rocking bearing for the upper portion of said spring suspended jaw, a link pivotally connected to the lower portion of said spring suspended jaw, a power driven shaft journaled in the frame of the machine, an eccentric carried by said power driven shaft, a lever having one end mounted on said eccentric, the other end of said lever being pivotally connected to said link and a link pivotally connected to the frame of the machine below said lever and said first mentioned link, the upper end of which last mentioned link is pivotally connected to the connected ends of said first mentioned link and lever to provide a swinging fulcrum for the connected ends of said first mentioned link and lever.

PASCAL SCHILZ.
